FUEL LINE TESTING

Bruno M. Ikert, Elgin, Ill., assignor to Warner-Patterson Company, Chicago, Ill., a corporation of Illinois

Application March 21, 1941, Serial No. 384,473

2 Claims. (Cl. 73—51)

This invention has to do with pressure testing apparatus and relates more particularly to apparatus connectible with the fuel feed line for engine-driven vehicles to facilitate ascertainment of whether an obstruction is lodged therein.

The primary object of the present invention is the provision of a novel and effective fuel line testing apparatus embodied in a simple structure that is conveniently attachable to a fuel feed line to enable one to immediately determine whether it is open or clogged.

A more specific object of this invention is the provision, in apparatus for testing the flow capacity of a fuel delivery line as for internal combustion engine, of a new fastening means substitutable for standard fastening means of said line but also having a passage functional in the provision of an operable communication between a pressure gauge and the interior of such line.

These and other desirable objects inherent in and encompassed by the invention will subsequently appear.

Reference should now be had to the annexed drawing, wherein:

Fig. 1 is a fragmentary sectional view of a pump and filter unit used in the fuel line of an automobile engine, and illustrating a preferred form of the invention attached in operative relation therewith; and

Fig. 2 is a sectional view taken axially through a bolt constructed in accordance with the principles of this invention.

There is shown in Fig. 1, a fuel pump and filter unit 10 including a cup-like casing wall member 11 of conventional structure and which is in the form of a complicated casting. A liquid fuel as gasoline is drawn into the unit 10 through a conduit 12 which leads from a fuel tank or reservoir (not shown). Such fuel is discharged from the unit through a conduit 13 which ordinarily leads to the engine carburetor, (not shown). Thus the unit 10 comprises a portion of the fuel feed line.

Communication of the conduit 12 with the interior of the unit is had by means of an opening 14 in the casting 11 and fuel passing inwardly of the unit through said conduit and said opening fills the cavity 15 in said casting and passes upwardly through a reticulated filter disk 16 which is clamped at its circumferential edge portion between the upper cylindrical end of the casting 11 and a circular seat 17 about the lower edge of a closure cap 18, the latter being pressed into shape from sheet metal. Said cap 18 is apertured at 19 to receive the shank of a bolt 20 of which the lower threaded end is turned into

a threaded recess 21 in an upwardly projecting boss 22 forming a part of the casting 11. Thus when the bolt 20 is turned downwardly into the recess 21 the head thereof will be brought to bear against a gasket 23 for sealing the opening 19 and for retaining the cap member 18 and the filter disk 16 tightly in sealing relation with the upper end of the member 11.

The filter disk 16 is provided with a substantially central opening 24 which slides closely over a reduced upper end portion of the boss 22 and fits snugly against a shoulder 25 upon said boss. An eccentrically disposed opening 26 in said filter disk receives an upper end portion of a second boss, 27, also integral with the casting 11, and its edge fits in sealing relation with a shoulder 28 on this boss member.

After the fuel is filtered by passing upwardly through the filter member 16, it passes downwardly through a passage 29 in the boss 27 and thence through a valve 30 and a channel 31 of the casting 11 into a chamber 32 formed between the lower end of the casting and a pump diaphragm member 33. The peripheral edge of the diaphragm 33 is hermetically clamped between a mounting member 34 for the casting 11 and an annular face portion 35 about the lower edge of said casting whereby a pulsating pressure condition can be created in the chamber 32 when the diaphragm is laterally deflected reciprocally by an operating stem 36 which in turn is operated by engine driven means (not shown).

The valve 30 is the intake valve and includes a reciprocal head 37 urged against a seat 38 by means of a spring 39. An exhaust valve unit 40 includes a rigid plate 41 having an opening 42 and hermetically connected over the mouth of an exhaust port 43 by any standard fastening means such as screws 44. A thin resilient metal flap 45 is connected to the member 41 at one side of the opening 42 and normally lies flatly upon the upper face of the member 41 in closing relation with said opening but is adapted to be flexed upwardly for uncovering such opening as in the manner illustrated.

In the operation of the pump and filter unit 10, while the diaphragm 33 is drawn downwardly into the position shown in dotted lines the pressure in the chamber 32 will be decreased whereby the valve head 37 will be unseated while compressing the spring 39 and fuel will be drawn into the chamber 32 from the fuel tank (not shown) through the conduit 12, the interior 15 of the casting 11, filter member 16, passage 29, the valve unit 30 and channel 31. Pursuant to the succeed-

ing upward stroke of the operating stem 36, the pressure in the chamber 32 will be increased to augment the force of the spring 39 in closing the intake valve unit 30 while pressing the resilient valve flap 45 upwardly for uncovering the opening 42 wherefore the fuel is forced outwardly of the chamber 32 through the port 43, a passage 46, and outwardly of the pump through the conduit 13 to the carburetor (not shown).

In the proper operation of a vehicle engine it is essential, of course, that the fuel line shall be unobstructed, and therefore the tuning or adjusting process for an improperly performing engine usually includes the step of ascertaining whether there is an obstruction in the fuel line. The contemporary method of executing this step is to disconnect the fuel line at an end where a source of compressed air can be connected and blowing a stream of such air into the line. Obviously this step is necessarily time consuming and is frequently unnecessarily performed because of the fuel line having been unobstructed. This invention contemplates a simplified structure which may be easily and quickly connected in the fuel line for testing whether the same is clogged and thus whether the step of blowing out an obstruction is necessary.

My improved testing apparatus includes a fastening member or bolt 47 shown in Fig. 2 which has physical characteristics and structure enabling it to be substituted for the bolt 20 insofar as concerns holding the cap 18 and the filter member 16 in assembly with the casting 11. The bolt 47, however, further includes a recess 43 counter-bored to form a passage 49. The passage 49 extends downwardly into the shank of the member 47 where it connects with a lateral bore 50. This passage 49 and bore 50 are superposed in dotted outline in Fig. 1 in association with the bolt 20 to illustrate the relation with respect to the unit 10 that these parts would occupy when the bolt 47 is substituted for the bolt 20. There is also shown in Fig. 1, a conduit 51 which connects with a vacuum or reduced pressure indicator gauge generally designated 52. It will be seen that when the bolt 47 is substituted for the bolt 20 that the gauge 51 will operatively communicate with the interior of the casting 11 through the conduit 51, the passage 49 and the bore 50. When the gauge 52 is so associated with the fuel line upon the upstream side of the inlet valve 30, the vacuum created at this section of the fuel line during operation of the pump diaphragm 33 will be of a normal amount when the fuel is being drawn through an unobstructed fuel line and a greater amount in the event said line should contain an obstruction. It may therefore be ascertained from the pressure reading of the gauge 52 whether the line is closed.

My improved apparatus is particularly unique and useful in that its part 47 for connecting with the fuel line uses the same threaded recess as standard fastening means and further in that 5 while said part is so connected it is also operable to perform the mechanical functions of the part which it temporarily replaces. Consequently no special accessories or machining are necessary for the fuel line in adapting it to be conveniently tested.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed:

1. In testing apparatus of the character described for testing the fuel line of an internal combustion engine in which the fuel line extends between a fuel tank and a suction chamber of a fuel pump and wherein said suction chamber has a removable wall portion fastened to the pump by a fastening member extending through the chamber; the combination of a member having mechanical features enabling it to be substituted for said fastening member and further having a channel communicative between the interior and the exterior of said chamber when so substituted, and a gauge for reading reduced pressure connected with said member and communicative through said channel with said chamber to indicate the degree of vacuum therein and hence whether the flow capacity of said line is normal.
2. In testing apparatus of the character described for testing the fuel line of an internal combustion engine in which the fuel line extends between a fuel tank and a suction chamber of a fuel pump and wherein said suction chamber has a removable wall portion fastened to the pump by a fastening member of which a portion projects through said chamber into screw-threaded relation with a part thereof for holding the parts of the chamber in assembly; the combination of a threaded member of dimensions enabling it to be substituted for the fastening member in performing the aforesaid mechanical function and further having a channel communicative between the interior and exterior of said chamber when so substituted, and a gauge for reading reduced pressures connected with said threaded member and communicative through the channel therein with said chamber to indicate the degree of vacuum therein and hence whether the flow capacity of the fuel line is normal.

BRUNO M. IKERT.
